UNITED STATES PATENT OFFICE

2,444,954

RAIL JOINT

George Rademaker, Chicago, Ill.

Application November 29, 1944, Serial No. 565,684

6 Claims. (Cl. 238—151)

1

This invention relates to a rail joint, and more particularly to such a joint adapted for use between the rails of railroad tracks.

A primary object of this invention is the provision of a rail joint having means for association therewith to allow for expansion and contraction of the rail, such as is occasioned by change in temperature, or the like.

An additional important object of this invention is the provision of such an expansion joint provided with means whereby the connection of adjacent sections of rail is effected without the provision of a low point or joint, as is conventional practice, thus obviating the greater effect of wear normally occasioned at such point.

Still another object is the provision of an improved rail joint so designed as to occasion less vibration and jolting, and consequently less wear and damage to the rolling stock of the line.

Still another object of this invention is the provision of such a joint which will be sturdy and durable in construction, reliable and efficient in operation, and which may be manufactured and installed with a relative minimum of expense and difficulty.

Still other objects reside in the combinations of elements, arrangements of parts, and features of construction, all as will be more fully pointed out hereinafter and shown in the accompanying drawings, wherein there is disclosed a preferred embodiment of this inventive concept.

In the drawings:

Figure 1 is a top plan view of one form of rail joint in accordance with the instant invention.

Figure 2 is a side elevational view of the device shown in Figure 1.

Figure 3 is a sectional view taken substantially along the line 3—3 of Figure 2, as viewed in the direction indicated by the arrows.

Figure 4 is a sectional view taken substantially along the line 4—4 of Figure 2, and

Figure 5 is an enlarged perspective detail view of a constructional element.

Like reference numerals refer to like parts throughout the several views of the drawings.

Having reference now to the drawings, there is shown at 10 a plurality of ties, upon which are adapted to be mounted rails, portions of which are shown at 11. Underlying the spaced extremities of adjacent rails 11 are positioned the extremities of a base plate 12 adapted to be secured to the ties 10, as by bolts or spikes 13.

Secured between and abutting the ends of rails 11, and mounted on base 12, are a plurality of plates, such plates taking two forms, one form 14

2

comprising short plates, and the other form 15 comprising long plates. The arrangement is such that two of long plates 15 and two of short plates 14 are positioned in alternately spaced abutting relationship with each of rail ends 11, and oppositely with respect to each other in such manner that oppositely disposed short and long plates are in aligned relationship.

Fish plates 18 are secured to the extremities of rails 11, as by bolts 19 and nuts 20, passed through suitable aligned bores in the rails and plates, and are also secured to the assembly adjacent the end of the rail comprised of the plates 14 and 15, similar bolts 19 and nuts 20 being passed through suitable aligned apertures through the component parts thereof. The nuts 20 are preferably of the lock nut type, and the bolts 19, if desired, may be passed through suitable sleeves 21 positioned within their associated bores.

As best shown in Figure 5, each of long plates 15 is provided with a plurality of transverse slots or apertures 22 therethrough, through which are adapted to be passed sleeves 21a of a length substantially equal to the thickness of the four plates, bolts 19a passing through such sleeves and being held in position as by lock nuts 20a.

In the normal assembly of the rail joint, the ends of plates 15 are spaced from the adjacent ends of plates 14 in such manner as to provide gaps 23 therebetween, the gaps occurring adjacent opposite ends of the rail point, in alternate relation, in accordance with the previously described arrangement of the plates, and the dimensions of the gap left being adjusted in accordance with the surrounding temperature under the conditions of laying the rail.

Now, from the foregoing, it will be seen that the opposite plates 15 comprise, in effect, due to the nut and bolt construction previously described, a continuation of their associated rail 11, and that, when any expansion or contraction in the rail occurs, the oppositely disposed gaps 23 will be varied accordingly, limited play between the adjacent plates 15 being permitted by the slots 22 and their associated nut and bolt connections.

As best shown in Figure 4, if desired, the inner of members 14 and 15 may be rectangular in cross section, and the outer members may be formed in conformity to the cross section of the rail of the rail, in such manner that the joint comprises in effect a continuation of the rail structure, forming, through the inter-engagement of plates 15, a continuous unbroken rail

surface which at the same time comprises an expansion joint.

Suitable apertures may be positioned in the base plate 12, if desired, in vertical alignment with the gap 23, to permit the escape of any dirt or foreign matter which might lodge therein when the rails were in contracted position.

From the foregoing, it will now be seen that there is herein provided an improved expansion joint for rails, accomplishing all the objects of this invention and others, including many advantages of great practical utility and commercial importance.

As many embodiments may be made of this inventive concept, and as many modifications may be made of the embodiment hereinbefore shown and described, it is to be understood that all matter herein is to be interpreted merely as illustrative and not in a limiting sense.

I claim:

1. In combination with a pair of aligned and longitudinally spaced rails, having pairs of fish plates directly connected thereto respectively, an expansion joint comprising a plurality of sets of vertical plates positioned between the ends of adjacent rail extremities and between said fish plates, alternate plates abutting opposite rail extremities and secured thereto by said fish plates, the other ends of said plates being spaced from opposite rail extremities, and means holding said plates in longitudinally slidable related assembly.

2. The combination of claim 1, wherein said means includes longitudinal slots in registerable position in said plates, and bolts extending through said slots.

3. A longitudinally expandable rail joint comprising a pair of aligned and spaced rails, a base plate underlying the adjacent extremities of said rails, pairs of fish plates secured to the outer sides of the adjacent end of each of said rails, sets of parallel plates secured by and between and extending longitudinally beyond said pairs of fish plates, said sets of parallel plates being interdigitated and having their upper surface forming a continuation of the balls of said rails, and means clamping said parallel plates together in

longitudinal, slidable engagement, vertical channels between the extremities of said rails and the ends of the parallel plates secured to the opposite rails, and drainage apertures in said base plate communicating with said channels.

4. An expansion joint for aligned and longitudinally spaced rails having pairs of fish plates directly connected thereto respectively, comprising a first set of parallel vertical plates abutting the extremity of said first rail and having their upper and side surfaces forming plane continuations of the corresponding surfaces of said first rail, means securing said set of plates between said fish plate and to said first rail, a second set of plates similarly secured to a second rail, means for clamping said sets in longitudinally slidable relation, said sets of plates being composed of alternate long and short plates, the long plates of one set being longitudinally aligned with and spaced from the short plates of the other set.

5. The combination of claim 4, each of said plates having its sliding engagement with the adjacent plates of the opposite set confined to vertical planes.

6. The combination of claim 4, wherein the outer plates of each set have their lower portions flared out into conformity with and seating engagement upon the foot of said rails.

GEORGE RADEMAKER.
